UNITED STATES PATENT OFFICE.

ECKARDT V. ESKESSEN, OF PERTH AMBOY, NEW JERSEY.

DUMMY AERIAL BOMB.

1,285,083.

Specification of Letters Patent. Patented Nov. 19, 1918.

Application filed March 16, 1918. Serial No. 222,916.

To all whom it may concern:

Be it known that I, ECKARDT V. ESKESSEN, a citizen of the United States, and a resident of Perth Amboy, in the county of Middlesex 5 and State of New Jersey, have made certain new and useful Improvements in Dummy Aerial Bombs, of which the following is a specification.

My present invention relates generally to 10 aerial bombs, and more particularly to dummy bombs utilized in training or instruction of bomb droppers, my object being the provision of a simple, inexpensive construction, whereby to permit of the manufacture of the body of the bomb from plastic material, and distribute the weight so that 15 the center of gravity may be located at the proper and desired point to permit of utilization of the bomb with practical efficient 20 results.

A further object of my invention is to provide an economical construction of the present character, the casing or shell of 25 which has its body formed of a suitable plastic material or composition of materials with means to secure a relatively lighter tail-piece carrying the guide wings, and with means holding the tail-piece in connection 30 with the body and a portion of which means serves also to properly distribute weight.

In the accompanying drawing illustrating 35 my present invention:

Figure 1 is a view partly in vertical longitudinal section through my improvements, and

Fig. 2 is a detail section enlarged through a portion of the wing supporting tail.

Referring now to these figures, the bomb 40 is in the form of a hollow shell or casing, the body 10 of which is cylindrical for the major portion of its length and tapers at one end 11 to an approximate point 12. The tapered lower or front end 11 of the body 10 is thus closed, while the rear end is open 45 and is provided with an annular groove tapered as seen particularly at the upper right portion of Fig. 1, the recess being indicated at 13 to receive the open enlarged 50 end or base of a conical tail-piece 14, supporting outstanding wings 15 connected by a reinforcing band, portions of which are seen at 16.

The conical tail 14 tapers to an apex lo-

cated in the axial plane of the body 10 at a point rearwardly beyond the rear end of the body, and between the inner rear edges of the wings 15, the said apex being best seen at 17, in Fig. 2, and having an opening 60 for the rear threaded end of a supporting rod 18, the threaded end of which is engaged by a nut 19, bearing against the apex 17 of the tail piece.

The rod 18 extends forwardly through 65 the tail piece 14, and through the body 10 for the major portion of the length of the latter, and is provided with a forward angular end 20 located within the forward portion of the hollow of the body 10, and 70 solidly embedded within a plastic filling 21, which serves to weight the forward end of the bomb, in order to bring the center of gravity approximately at the line indicated in Fig. 1.

It is obvious that more or less plastic filling 21 may be required as the particular material of which the body 10 is formed, 75 may be varied, and it is equally obvious that irrespective of the particular amount of such plastic filling, the forward inner end of the rod 18 will be firmly embedded and sufficient support afforded the same to enable it to firmly and uniformly secure the tail piece 14 in its seated relation at the rear end of the body.

As at present contemplated the body 10 may be formed of terra cotta, but it is obvious that this material may be changed as 90 well as the material of which the tail-piece 14, and wings 15 are formed.

I claim:

1. An aerial bomb of the type described comprising a hollow cylindrical body closed 95 at one end and open at its opposite end, a hollow tail piece at the open end of the body, and having guiding wings, a rod extending axially through the body and having means at one end to engage the tail piece, and a 100 plastic weight distributing material within the hollow closed end of the body in which the opposite end of the rod is embedded for the purpose described.

2. An aerial bomb of the type described 105 consisting of a body portion closed at one end and open at its opposite end, a rod projecting axially within the body and beyond the open end thereof, a plastic weight distributing material within the hollow body 110

adjacent its closed end and in which one end of said rod is embedded and firmly held, the rearwardly projecting end of the rod being threaded, a hollow tail piece carrying 5 wings, and through which the threaded end of the rod projects, said tail piece being positioned at the open end of the body, and a nut engaging the threaded end of the rod

outwardly beyond and bearing against the said tail piece, to secure the latter in position.

ECKARDT V. ESKESSEN.
